UNITED STATES PATENT OFFICE.

CHARLES JAMES, OF RUTHERFORD, NEW JERSEY.

DRIFTING-VALVE.

1,111,903.

Specification of Letters Patent. Patented Sept. 29, 1914.

Application filed November 25, 1913. Serial No. 802,903.

To all whom it may concern:

Be it known that I, CHARLES JAMES, a citizen of the United States, and a resident of Rutherford, in the county of Bergen and State of New Jersey, have invented a new and Improved Drifting-Valve, of which the following is a full, clear, and exact description.

Among the principal objects which the present invention has in view are: to provide means for supplying low-pressure steam to the cylinder of a locomotive while the same is drifting, the supply being diminished and determined as the progress of the locomotive diminishes and ceases; to provide means, operated mechanically in unison with the moving parts of the locomotive, for controlling the supply of steam to the cylinders; and to provide a mechanism for attaining the above-stated objects, which is simple and effective in construction and operation.

The drawing is a longitudinal section taken on the median line of a valve and operating mechanism therefor, constructed and arranged in accordance with the present invention.

The valve casing 5 may be mounted in any convenient location to the mechanism in conjunction with which the valve herein described is operated. The prime consideration involved is the disposition of the connecting rod 6, which unites operatively the cross-head of the valve stem of a locomotive and the rocker arm 7 of the present apparatus. The casing 5 is bored to form two chambers of unequal diameter, the larger chamber 8 providing a cylinder for a floating piston 9, while the smaller chamber 10 is provided with a lining 11, bored and ported to receive a valve piston 12. The pistons 9 and 12 are rigidly connected by a stem 13, and are provided with packing rings 14 and 15, respectively.

The pistons 9 and 12 are of relatively different diameters, to expose different areas to steam delivered by a pipe 16 from the turret of the locomotive, to the chambers 10 and 8, and between said pistons. The superior area presented by the piston 9 results in moving the two pistons and connecting stem to the position shown in the drawings, where the piston 9 rests against the head 17 of the casing 5. The head 17 is centrally bossed to arrest the piston 9 in

position to form a space 18 between the head 17 and said piston, to clear the ends of passages 19, 20 and 21. The passage 19 is exposed to the surrounding atmosphere to permit the air behind the piston 9 to escape therefrom and avoid cushioning said piston.

In the position of the piston 9 above described, the piston 12 rests between the port 22 with which the pipe 16 is connected and ports 23 opening through the lining 11 to an annular chamber 24, which is in turn connected with a pipe 25. The pipe 25 is in direct communication with the steam-chest of one or more of the cylinders of the locomotive.

When the piston 12 is held in the position shown in the drawings, it is obvious that the steam entering from the pipe 16 does not flow through the ports 23 and pipe 25. As long as the throttle is open to supply steam to the steam-chest of the cylinders, the overbalance of the pressure of steam in the chamber 10 exerted on the piston 9 retains the combined pistons 9 and 12 in the position shown in the drawings. When, however, the power steam is cut off, the pistons 9 and 12 are moved by the pressure of air in the space 18, backward until the piston 12 rests upon a boss 26 formed of a head 27, which closes the end of the casing 5. The air pressure, as hereinafter explained, lessens and finally determines with the suspension of movement of the locomotive. When the air pressure is thus determined in the space 18, the overbalance of steam in the chamber 10 from the pipe 16 exerted on the piston 9 moves the combined pistons 9 and 12 to the position shown in the drawings. In this position, the relatively low-pressure steam in the chamber 10 is prevented from passing to the power cylinders of the locomotive, with the possible consequence of building up in said cylinders sufficient pressure to move the same and cause the locomotive to creep.

The air pressure in the space 18 is produced by operation of the plunger having the piston 28. The piston 28 is reciprocally mounted in a cylinder 29 rigidly or integrally formed on the head 17 of the casing 5. The space 18 at the end of the chamber 8 is held in communication with the compression end of the cylinder 29 through the passage 20 when a valve 30 lifts.

The valve 30 is seated by a spring 31, and opens outwardly from the cylinder 29 to permit the air compressed in the forward end thereof to escape through the passage 5 20 to the space 18 of the chamber 8. Air is drawn into the cylinder 29 when an intake valve 32 lifts, a passage being formed in a nut-head 33 to supply said cylinder 29.

The piston 28 is rigidly mounted on a 10 piston rod 34, the outer end whereof is slidably mounted in a bearing formed in a bracket 35 of a yoke 36. The piston rod 34 is provided with pins 37 extending from both sides of said rod through bearings 38 15 formed in the rocker arm 7. The rocker arm 7 is provided at the lower end with an elongated slot 39 to engage pins 40 extending from both sides of the yoke 36. It is upon the pins 40 that the arm 7 fulcrums, 20 the slot 39 permitting the relative adjustment of said arm to the pins 40 necessary to maintain the straight-line thrust of the rod 34. As above stated, the rocker arm 7 is preferably operated from the valve-stem 25 cross-head, the stroke whereof is relatively slow and short. It will be understood that by varying the relative length of the upper and lower extensions of the arm 7, the stroke of the piston 28 may be varied.

30 The pressure of air in the space 18 of the chamber 8 is at all times maintained by a relief valve 41. The valve 41 is held seated by a spring 42, the tension whereof is varied by a follower nut 43, which is locked in position by a lock-nut 44. The nut 43 is held in a valve casing 45, which is supplied with side openings 46 to permit the escape of air from under the valve 41 through the passage 21, from the space 18 whenever the 40 pressure in said space overbalances the pressure on the valve 41 exerted by the spring 42.

The pressure normally maintained in the space 18 is greater than the overbalance of the respective pressures of steam upon the 45 pistons 9 and 12. The air in the space 18 is normally prevented from moving the pistons 9 and 12 by the steam delivered into the lower end of the chamber 10 on the far side of the piston 12 by the pipe 25. It will 50 be understood that as the pressure of air produced by the piston 28 depends upon the movement of said piston, and the movement of said piston depends upon the movement of the locomotive, the steam admitted 55 to the power cylinders of the locomotive enters the lower end of the chamber 10 in the chamber 5 before the air pressure in the space 18 is built up to its normal. In this condition, it will be seen, the pistons 9 and 60 12 are maintained in the position shown in the drawings by the united effect of the overbalance of steam from the pipe 16 and the direct pressure of steam from the pipe 25. It is after the pressure of steam in the 65 pipe 25 determines, that the pressure of air

in the cylinder 29 and space 18 operates to move the pistons 9 and 12 to expose the ports 23.

When, in the course of operation, the running speed of the locomotive diminishes or ceases, the operation of the piston 28 likewise slows or ceases, and the pressure of air behind the piston 9 diminishes and vanishes. When the pressure of air behind the piston 9 falls below the overbalance of pressure 70 exerted by the steam from the pipe 16 on the piston 9, as compared with the pressure exerted by it upon the piston 12, the combined pistons are moved toward the opposite end of the casing 5, first covering the 75 ports 23, and finally resting between the ports 22 and 23 in the position shown in the drawings.

The passages 19 and 46 are small passages 80 to prevent the trapping of air or steam behind the pistons 9 and 12 when moved toward the respectively adjacent ends of the casing 5.

Claims.

1. In combination with a locomotive having power cylinders, a power source, and running gear; a valve comprising a casing 90 having inlet and outlet ports; a valve piston movable in said casing to cover said outlet port; a floating piston operatively connected with said valve piston; means operatively connecting said power source and floating piston to move said valve piston to close said outlet port; an air-pressure mechanism operatively connected with said floating piston to move the same in opposition to said power source; and a relief valve for said air-pressure mechanism, to regulate the maximum pressure thereof.

2. In combination with a locomotive having power cylinders, a power source, and running gear; a valve comprising a casing having inlet and outlet ports; a valve piston movable in said casing to cover said outlet port; a floating piston operatively connected 105 with said valve piston; means operatively connecting said power source and floating piston to move said valve piston to close said outlet port; and an air-pump operatively connected with said running gear, 110 arranged to deliver into said casing, at the far side of said floating piston, to move the same in opposition to the pressure of said power source.

3. In combination with a locomotive having power cylinders, a power source, and running gear; a valve comprising a cylindrical casing interposed between said power source and power cylinders, said casing having longitudinally separated inlet and outlet ports; a valve piston to expose and close said outlet port; a floating piston of relatively larger diameter operatively mounted in said casing; a piston rod connecting said pistons, said rod being arranged 125 120 125 130 135 140 145 150 155 160 165 170 175 180

to maintain said pistons continuously at opposite sides of said inlet port; an air-compression pump operatively connecting said casing, to deliver air under pressure between said floating piston and the adjacent head of said casing, to move said valve piston to expose said outlet port and establish communication between the inlet and outlet ports; and means operatively connected with 10 said running gear for operating said pump.

4. In combination with a locomotive having power cylinders, a power source, and running gear; a valve comprising a cylindrical casing having inlet and outlet ports longitudinally separated therein; a valve piston to normally rest between said ports; a floating piston having a relatively larger diameter, disposed at the side of said inlet

port opposite that where said valve piston rests, to secure an unbalanced pressure between said pistons; a piston rod rigidly connecting said pistons; an air pump operatively connected with said running gear to deliver air under pressure at the far side of said floating piston; and a relief valve 25 opening from said casing to operate at a pressure greater than the said unbalanced pressure exerted on said pistons.

In testimony whereof I have signed my name to this specification in the presence 30 of two subscribing witnesses.

CHARLES JAMES.
